UNITED STATES PATENT OFFICE.

WILLIAM VOGLER, OF SOMERVILLE, MASSACHUSETTS.

INSULATOR.

SPECIFICATION forming part of Letters Patent No. 445,008, dated January 20, 1891.

Application filed May 23, 1890. Serial No. 352,841. (No model.)

To all whom it may concern:

Be it known that I, WILLIAM VOGLER, of Somerville, county of Middlesex, State of Massachusetts, have invented an Improvement in Insulators, of which the following description, in connection with the accompanying drawing, is a specification, like letters on the drawing representing like parts.

This invention relates to insulators especially adapted to be used in the overhead system of electric railways as a support for the usual trolley-wire.

In practice it has been demonstrated that many compositions which are excellent insulators in themselves are unfitted for use as an insulator for the overhead trolley-wire, owing to the liability of the said insulating material being melted by sparks or flashes of the current between the trolley-wheel and the trolley-wire.

My invention has for its object to provide an insulator capable of resisting the action of the electric flash or spark, whereby the compositions heretofore unfitted for service on electric railways may be used.

In accordance with my invention the insulator is composed of a central portion of insulating material of high insulative capacity and an outside or protective covering of insulating material of a lower insulative capacity, but of a higher refractory nature. The central body portion of the insulator in practice will preferably be molded around a sleeve threaded on its inner side to engage the threaded shank of a bolt or hanger to which the trolley-wire is secured, and the outside or protective covering is molded upon the central insulating-body.

My invention therefore consists in the herein-described insulator, it consisting of an inner body of high insulating capacity and an outer body of high refractory nature protecting the inner body, substantially as will be described.

The drawing is a longitudinal vertical section of one form of insulator embodying my invention, the said insulator having secured to it the usual trolley-wire.

My improved insulator consists of an inner or central body *a*, herein shown as cone-shaped, it being composed of material of a high insulating capacity. The inner body *a* has molded about it an outer body *a'* of a lower insulating capacity than the body *a*, but of a more refractory nature, the said outer body *a'* completely enveloping the high-insulating body *a*, so that the latter is completely protected from sparks or flashes, which in practice might arise by the breaking of the contact between the usual trolley-wheel (not shown) and the trolley-wire *b*. The trolley-wire *b* is herein shown as secured to a hanger *b'*, (shown as a rod or bolt threaded at its upper end and extended up through the under side of the insulator into a threaded sleeve 65 or nut *b*), about which the insulating-body *a* is first molded.

The insulator in practice is suspended, as herein shown, by means of a wire *c* and branch wires *c'*, secured to the said wire and 70 to a wire *c*, herein shown as located in a groove formed in the surface of the outer body *a'* near the base of the insulator; but I do not desire to limit myself to the particular manner shown for suspending the insulator, as it may be suspended in any usual or well-known manner.

I have herein shown my improved insulator as cone-shaped; but I do not desire to limit myself in this respect, as the said insulator may be of any desired form.

It will be noticed that the insulating inner body *a*, which is of high insulative capacity, is completely protected by the outer body *a'*, which is of a lower insulative capacity, but of a higher refractory nature, so that it is unaffected by the sparks or flashes.

The inner body *a* may be made of any of the high insulating compositions now known to electricians, and the outer body may be 90 made of pulverized broken glass or asbestos cemented together by a water-proofing material.

I claim—

1. The herein-described insulator, it consisting of an inner body of high insulating

capacity and an outer body of high refractory nature protecting the inner body, substantially as described.

2. The herein-described insulator, it consisting of an inner body of high insulating capacity and an outer body of high refractory nature enveloping the inner body, substantially as described.

In testimony whereof I have signed my name to this specification in the presence of two subscribing witnesses.

WILLIAM VOGLER.
